UNITED STATES PATENT OFFICE.

CHARLES E. RICE, OF SANFORD, FLORIDA.

COOLING DEVICE FOR OILS.

Application filed November 14, 1922. Serial No. 600,981.

To all whom it may concern:

Be it known that I, CHARLES E. RICE, a citizen of the United States, residing at Sanford, in the county of Seminole and State of Florida, have invented certain new and useful Improvements in Cooling Devices for Oils, of which the following is a specification.

The present invention relates to a cooling device and has for its principal object to provide means for cooling the lubricating oil of an internal combustion engine.

Another important object of the invention is to provide a device of this nature which will be simple and efficient in construction, reliable in operation, comparatively inexpensive to manufacture and well adapted to the purpose for which it is designed.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

In the drawings:—

20 Figure 1 is a perspective of the device, Figure 2 is a perspective showing the jacket and coil,

Figure 3 is a perspective of the radiator, Figure 4 is a front elevation thereof,

35 Figure 5 is a transverse section through the device taken substantially on line 5—5 of Figure 6, and

Figure 6 is a central longitudinal section therethrough.

40 Referring to the drawings in detail, it will be seen that 1 designates a jacket or drum which is provided at its rear end with a flange 2; a coil 3 is disposed within the jacket having an inlet 4 extending therethrough, and an outlet 5 extending therethrough adjacent the ends thereof. The jacket is provided with a filling neck or inlet 6 having a closure cap 7 thereon.

50 A cooling device is disposed within the jacket 1 and the coil 3 for the purpose of cooling the contents of the coil 3. In the cooling device is included a drum 8 which is provided with a plurality of apertures 9. A plurality of tubes 10 connect the apertures 9 as is illustrated to advantage in Fig. 5 it being noted that the tubes extend parallel with

each other and preferably vertical although this is not necessary. A flange 11 is fixed to the forward end of the drum 8. The drum 8 is constructed so as to telescope within the jacket 1 and coil 3 and is held in place by the bolts 12 which pass through the flanges 11 and 2. Suitable gaskets 13 are disposed between the flange 2 and the rear end of the drum 8 and also between the forward end of the drum 1 and the flange 11. It is to be understood that water is placed in the jacket 1 and tubes 10.

The forward end of the drum 8 is provided with internal threads for receiving the 79 threaded flange 13' of the cone shaped extension 14. A shaft 16 is journaled centrally and longitudinally of the extension 14 by suitable brackets 17 and a fan 18 is rotatable on this shaft 16 being provided 75 with the hub 19 having keyed thereto a pulley 20 so that a belt may be trained thereover and driven by the engine or other suitable means.

The oil of the internal combustion engine 80 will be pumped through the coil 3 and will be cooled by the water in the jacket 1 and tubes 8 which water in turn will be cooled by the air passing through the drum 8 caused by the forward movement of the vehicle 85 upon which the internal combustion engine is mounted and also by the fan 18. It is thought that the advantages and construction of the invention will be clearly understood without a more detailed description 90 thereof. It is desired, however, to point out that the device will act efficiently for cooling the oil and at the same time is constructed so that it may be readily assembled and disassembled for cleaning and repair purposes. 95

Having thus fully described my invention what I claim is:—

1. In combination, a jacket having a flange at one end, a coil disposed within the 100 jacket, a drum having a flange at one end opposite the flange on the jacket, said drum disposed within the coil and the jacket, means for engaging the flanges so as to hold the jacket and drum together, and form a 104 compartment therebetween, a plurality of tubes extending transversely of the drum and communicating with said compartment.

2. In combination, a jacket having a flange at one end, a coil disposed within the 110 jacket, a drum having a flange at one end opposite the flange on the jacket, said drum

disposed within the coil and the jacket, means for engaging the flanges so as to hold the jacket and drum together, and form a compartment therebetween, a plurality of tubes extending transversely of the drum and communicating with said compartment, and an extension at one end of the drum.

In testimony whereof I affix my signature in presence of two witnesses.

CHARLES E. RICE.
